JOHN M. CORNELL, OF SEA BRIGHT, NEW JERSEY.

AUTOMATIC FIRE SHUTTER.

Application filed June 2, 1925. Serial No. 34,283.

This invention relates to that class of fire-resisting shutters or doors which are normally held in raised or open position, but which are designed to be automatically released and closed upon a predetermined rise in temperature, as in case of fire. A shutter of the type in question is disclosed in Letters Patent No. 1,530,652, issued to Milton L. Cornell, March 24, 1925.

10 Shutters of this type are frequently installed at the opposite sides of door or window openings in the walls of buildings, in which event each shutter is independent of the other, each being equipped with its own 15 operating mechanism. Aside from the matter of the extra fire protection given by these double shutters, there are many objections to the same as heretofore installed, that is, for independent operation. For instance, in case 20 of fire, where both doors have automatically closed as the result of the fusing of the fusible link or links comprised in the shutter operating mechanism, any one endeavoring to 25 escape through the opening would be obliged to lift both doors separately, and the delay thus caused might prove fatal. Again, in case of fire on only one side of a party or division wall, the shutter on that side might drop and be partially destroyed by fire before 30 the opposite shutter or door came down, in which event the double protection provided for would not be effective. These disadvantages, as well as many others not referred to, resulting from the independent operation 35 of the double shutters, are such as to practically offset the advantages of the extra fire protection afforded by the same. It has therefore been the object of my present invention to provide an improved construction 40 of double shutter in which the disadvantages incident to the use of two independently installed and operated shutters will be avoided. This I accomplish by operatively connecting two rolling shutters, preferably through 45 gearing, whereby they will be caused to raise and lower in unison, and associating an operating mechanism with only one of the shutters; this operating mechanism, by reason of the connection between the shutters, being 50 effective to simultaneously operate and control both shutters.

By thus operating both shutters as a single unit through the instrumentality of one operating means, the objections heretofore noted in connection with the use of two independently operated shutters are avoided;

also, a substantial saving in expense is obtained by eliminating one of the operating means, and a substantial saving in time in the operation of the shutters obtained by reason of the operation of one effecting the operation of both.

Referring now to the accompanying drawings forming part of the specification.

Fig. 1 is a front elevation of a wall having 65 a door or window opening to which my improved shutter has been applied, the shutter supporting and operating mechanism being partly broken away and in section.

Fig. 2 is an enlarged section on the line 70 2—2 of Fig. 1.

Fig. 3 is a section taken vertically through the upper end of a door or window opening, in which is installed a shutter constructed in accordance with my invention. 75

Figs. 4, 5 and 6 are similar views showing variations in the positions and connections of the parts for adapting them to openings of different wall thicknesses.

As one of the shutters or doors of the present invention, with its supporting and operating mechanism, may be of any usual or suitable type, I have here shown one corresponding with that of the aforesaid Patent No. 1,530,652. According to this, the shutter or door 10 is adapted to close an opening 12 in a wall 13, the same being guided in its raising and lowering movements by channel bars 14 positioned adjacent one side of the wall opening, that is, at one side of the opening in the direction of the wall thickness. This shutter, when in raised position, is in the form of a roll wound upon a barrel 17, to which it is connected, as shown in Fig. 1, by spacing collars 18 fixed to the barrel by screws 19, the shutter being attached at one end to said collars by screws or rivets 18'. The barrel 17 is in turn mounted upon a shaft 20 which extends therethrough and is journaled adjacent its opposite ends in the usual end brackets 26 fastened to the building wall or other support. The connections between said barrel and shaft comprise bushings 21 and 22 surrounding the shaft and secured by fastening devices 100 17" to the interior of the barrel and to the shaft, respectively, and a helical spring 23 fixed at one end to the bushing 21 and at its other end to the bushing 22. The spring 23 may be wound up or placed under tension by 105 a turning of the shaft 20 so as to normally counterbalance any tendency of the raised 110

shutter to descend; and its tension is preserved by locking the shaft against rotation by means of an automatic release mechanism.

Referring to Fig. 2, there is shown one form of automatic release mechanism comprising a toothed wheel 30 fixed to the end of the shaft 20 outside of one of the end brackets 26, and cooperating with said teeth is a detent 32 on a pivoted lever 33, said detent being here shown in the form of an anti-friction roll. The lever 33 is normally held so that the detent 32 engages with the teeth of the wheel 30 to hold the shaft 20 against rotation, by means of a bell-crank 35 pivoted on the bracket, one arm 36 of which carries an anti-friction roll 34 which normally engages the lever 33 to render the detent 32 effective, while the other arm 37 is normally held in raised position by a connecting chain 38 extending through the housing of the bracket 26 and held taut. In the chain 38 are located one or more fusible links 39 which, upon a given rise in temperature, will fuse and allow the chain 38 to slacken. The arm 37 of the bell-crank 35 is heavily weighted, so that upon the slackening of the chain it will descend, swinging the roll 34 on the arm 36 into engagement with a hook 31 at the under side of the lever 33 and positively rotating the latter downwardly to swing its detent roll 32 out of engagement with the toothed wheel 30. The full tensional force of the spring 23 is now effective to rotate the shaft 20 and the latter is given a rapid and strong rotary impulse, which is in the direction of the unwinding of the shutter and is utilized to operate an automatic starter for positively starting the shutter downwardly. As this starter however is not necessary to the operation of the shutter, and furthermore, as it forms no part of the present invention, no detailed description of the same will here be given, it being understood that after the tension of the spring 23 is released in the manner described and the shaft 20 thereby given an initial rotatory movement to start the shutter on its downward or closing movement, the weight of the shutter will be sufficient to rapidly carry it to closed position.

Referring now to Fig. 3, the shutter 10 at the left side thereof and its supporting and operating mechanism corresponds with that shown and described in connection with Figs 1 and 2, with the exception that the rolling shutter 10 is attached at its upper end directly to the barrel 17, as at 50, instead of indirectly thereto through the medium of spacing collars 18, as shown in Fig. 1. This difference however in no way effects the operation of the parts. In accordance with the invention as shown in this Fig. 3, a second shutter 10' is located adjacent that side of the wall opening 12 opposite the shutter 10 for sliding movement in vertically arranged channel guides 14' and is attached at its

upper end to a barrel 17' mounted on the shaft 20', which latter is journaled at its opposite ends in the brackets 26 carrying the shaft 20 for the first shutter 10. For causing the shutter 10' to be raised and lowered in unison with the first shutter 10, its barrel 17' is operatively connected with the barrel 17 of the first shutter through suitable gearing, shown in Fig. 3 as comprising two intermeshing spur gears 60 fixed on the respective barrels 17 and 17'. With this connection between the two shutters, it will be clear that all movements of the first or power shutter 10, both as thermally and otherwise controlled, will be imparted to the second shutter 10'. The advantages of thus operating the two shutters as a single unit, as to matters of increased safety, saving of time and greater convenience in operation, greater economy in construction through the elimination of the operating mechanism for one shutter, etc. have been hereinbefore referred to.

As to the feature of control of the automatic release for the operating spring 23 and connected shutter-carrying shaft, through the fusing of one of the fusible links 39 in the lever holding chain 38, I prefer to run chains to opposite sides of the wall opening and locate fusible links in the chains at such opposite sides as shown in Fig. 2, so that the shutters may be quickly released and closed as the result of a fire occurring at either or both sides of such opening.

In Fig. 4 I have shown the same parts as shown in Fig. 3, but rearranged to adapt them to a wall opening of less depth than that of Fig. 3, the rearrangement comprising the placing of the supporting shaft and associated parts of one shutter above those of the other, whereby the two shutters will be brought closer together as shown.

In Fig. 5 a similar combination of parts is shown with an operative connection between the shafts of the two shutters comprising a train of four gears 61, the two intermediate gears being arranged in a plane below that of the two gears on the shutter shafts.

In Figs. 3, 4 and 5, the shutters are shown as located within the opposite sides of the door opening. In Fig. 6, I have shown the parts applied to the opening of a relatively thin wall and with the shutters positioned outside of the door opening. With the shutter so positioned, any one of the arrangements of operating parts shown in Figs. 3, 4 and 5 may be employed, but as here shown I mount the shutter supporting shafts in projecting positions at the opposite sides of the wall and connect them by gearing 62.

What I claim is:

1. In combination, a pair of spaced rolling fire shutters adapted to close both sides of an opening, one only of which includes a spring actuated barrel tending to unwind

- the shutter and the other mounted on a plain barrel, means connecting the barrels to effect simultaneous operations thereof in the same direction, and thermally controlled means to 5 release the spring actuated barrel and permit the closing of both shutters, said thermally controlled means including heat responsive means located adjacent the respective sides of the opening.
- 10 2. In combination, a pair of spaced rolling fire shutters adapted to close both sides of an opening, one only of which includes a spring actuated barrel tending to unwind the shutter and the other mounted on a plain barrel, means connecting the barrels to effect simultaneous operations thereof in the same direction, a latch controlling the spring actuated barrel to hold both shutters in open position, and thermally controlled means for releasing 15 said latch to permit the closing of both shutters, said thermally controlled means including heat responsive means located adjacent the respective sides of the opening.
- 20 3. In combination, a pair of spaced rolling fire shutters adapted to close both sides of an opening, one only of which includes a spring actuated barrel tending to unwind the shutter and the other mounted on a plain barrel, means connecting the barrels to effect simultaneous operations thereof in the same direction, a latch controlling the spring actuated barrel to hold both shutters in open position, a lever holding the latch in engagement 25 with said barrel, and a chain extending 35 through the opening having a pendent link engaging the lever, and fusible links adjacent the respective sides of the opening.
4. In combination, a rolling fire shutter, operating means therefor including a spring actuated barrel tending to unwind the shutter, a second rolling fire shutter mounted upon a plain barrel spaced from said first-mentioned one, means operatively connecting the two barrels for effecting their movements 40 in unison to lower the shutters under the control of the said operating means for the first barrel, and thermally controlled means adjacent each shutter connecting with and effecting automatic operation of the first shutter 45 operating means.
5. In combination with a wall having an opening therein, a rolling fire shutter at one side of said opening, operating means therefor including a spring actuated barrel tending 50 to unwind the shutter, a second rolling fire shutter mounted on a plain barrel at the opposite side of said opening, means operatively connecting the two barrels for effecting their movements in unison to lower the shutters under the control of the said operating means for the first barrel, and thermally controlled means at the opposite sides of said opening connecting with and effecting automatic operation of the first shutter 55 operating means.

In testimony whereof I affix my signature.
JOHN M. CORNELL.
